UNITED STATES PATENT OFFICE.

CHARLES T. BOYER, OF INDIANAPOLIS, INDIANA.

COMBINATION TABLE AND CHINA CLOSET.

Application filed August 7, 1922. Serial No. 580,075.

To all whom it may concern:

Be it known that I, CHARLES T. BOYER, a citizen of the United States, residing at Indianapolis, in the county of Marion and 5 State of Indiana, have invented a new and useful Combination Table and China Closet, of which the following is a specification, reference being had to the accompanying drawings and to the letters and figures of reference marked thereon.

10 This invention relates to a type of household furniture in which is combined a china closet and a folding table and other useful features, and has reference more particularly to such combination article as is adapted to be permanently built into a dwelling.

15 An object of the invention is to provide a combined table and china closet which shall be so constructed as to be adapted to be connected with an apartment wall and in small spaces and which, when not in use, shall not occupy space in the apartment which in many cases is small.

20 Another object is to provide a combination folding-table and closet of such construction that the table when not in use shall perform the function of a closet door, and which may be simply constructed and operated.

25 A further object is to provide a folding-table of such construction as to be adapted to be pivotally supported and so counter-balanced as to permit the table to be easily supported and controlled.

30 A still further object is to provide a china closet suitable for a dining-room and a folding dining-table connected therewith, and also a disappearing door or closure for the closet to co-operate with the dining-table.

35 A still further object is to provide a dining-room with an artistic, unobtrusive and substantial dining-table and china closet combined which when not in use shall appear as a different article of furniture having a mirror, or as a draped wall panel, permitting the use of the entire apartment or chamber as a sitting-room or as a sleeping-room.

40 With the above-mentioned and other objects in view, the invention consists in a combination household article having various novel features embracing an improved dining-table and arrangement thereof in connection with a closet; the invention consisting 45 also further in the parts and combinations

and arrangements of parts as hereinafter particularly described and further defined in the appended claims.

50 Referring to the drawings, Figure 1 is a front elevation of a portion of an apartment wall and the invention associated therewith; Fig. 2 is a front sectional elevation partially broken away on an enlarged scale, elements or portions not necessary to an understanding of the invention being omitted; Fig. 3 is a fragmentary horizontal section of the wall portions of the china closet in which the improved dining-table is arranged in horizontal position, a portion of the table being broken away; Fig. 4 is a 55 transverse vertical section of the china closet and the dining-table folded up therein and constituting a closet door and also a mirror frame or holder; Fig. 5 is a perspective view of the combination table and closet arranged 60 as when the table is intended to be used; Fig. 6 is a perspective view of a part of the dining-table counter-balance; Fig. 7 is a fragmentary detail on an enlarged scale 65 illustrating particularly the pivotal support of the table and also a friction brake to check the movement of the table when swung upward; and, Fig. 8 is a fragmentary detail, being partially in section on a plane at 70 right angles to the preceding figure.

75 Similar reference characters in the different figures of the drawings indicate corresponding elements or features of construction herein referred to in detail.

80 In the drawings, the numeral 1 indicates 85 the wall of a dining-room or apartment, and 2 the base board usually arranged upon the floor against the wall of the apartment. The wall has a suitable opening at the sides of which are frame studs 3 and 4 provided 90 with frame facings 5 and 6 respectively that extend upward from the base board, a top facing 7 being connected to the other facings. A panel rail 8 is horizontally arranged at a suitable height and connected 95 to the vertical facings 5 and 6, and the lower portion of the opening in the wall is closed by a panel 9 connected with the rail and the base board and also with the vertical facing 5 and 6, to conceal the counter-balance of the dining-table. The closet has sides 10 and 11 extending back from the frame studs and it has also a back 12 connected with the sides, such back being a portion 100 of the wall which usually divides a 105 110

kitchen or a kitchenette from a dining-room. The closet has also a suitable top 13 which may be a portion of the dividing wall.

A suitable flat table 14 is provided which 5 has beams 15 and 16 secured thereto, being on the under side of the table when horizontal and extending over the rail 8. The beams are pivotally connected to the frame studs 3 and 4 by means of suitable pivot 10 devices 17 and 18 respectively, the devices preferably being composed of lag screws which are screwed into the studs and through suitable holes in the beams, there being preferably a space washer 19 on each 15 pivot or device between the stud and the adjacent beam. The table has a back board 20 at its rearward end to prevent articles falling from the table into the closet. The beams extend beyond their pivots so that the 20 rearward portions shall constitute counter-balance arms 21 and 22 that are provided respectively with relatively angular arm portions 23 and 24 that extend upward when the table is in horizontal position, and the 25 arm portions are provided with suitable pivots 25 and 26 respectively to which chains or links 27 and 28 are connected, which support a vessel 29 that is approximately 30 trough shaped and is partially filled with gravel or sand, or a mixture of both, to constitute a counter-balance weight 30 which may be readily varied, to effect adjustment so as to permit the table to rest when horizontal and to hold the table when pushed to 35 upright position.

A suitable brake or check is provided which may suitably comprise a base 31 secured to the frame stud 3 and having an elastic plate 32 fixed thereon and arranged 40 below the pivot 17 to be frictionally engaged by the arm 21 as the table approaches upright position. The table preferably has a handle 33 at the free end thereof whereby to pull the table from upright position. The 45 table is suitably stopped when moved downward to horizontal position, as by stop blocks adjacent to the back 12 to be engaged by the arms 21 and 22.

In order to avoid crowding of an article 50 of furniture in the apartment in order to have the use of a mirror, the table 14 is provided with a frame 34 between the beams 15 and 16, the frame supporting a mirror 35, the mirror preferably leaning forward at its top when the table is folded.

The closet is provided with any desired or 55 suitable number of shelves, there being a lower shelf 36 arranged in such position as to be immediately above the back board 20 when the table is in horizontal position, other shelves 37 and 38 being arranged so as to be behind the upright table which performs the function of a door to close the spaces above the shelves. Other shelves 39 60 are arranged above the others above-men-

tioned, and short compartment shelves 40 may be provided when desired between other shelves.

The upper portions of the facings or casing boards 5 and 6 are provided with combination brackets 41 and 42, or the brackets may be secured to the top facing 7, and they support a suitable roller 43 on which is rolled a flexible shade 44 constituting a door to be drawn down and constitute a closure 75 or cover for the articles in the closet.

Preferably a curtain pole 45 is supported on the brackets 41 and 42 and supports suitable curtains 46 and 47 arranged to be draped over pegs 48 and 49 respectively, 80 adjacent to the side facings 5 and 6 respectively.

In practical use, such articles as may be desired are placed on the shelves in the closet and may be concealed from view and also 85 protected from dust in the atmosphere. The table is easily drawn forward by means of the handle 33 until the pivots 25 and 26 are carried up and the table approaches horizontal position, the force of the counter-weight 90 becoming reduced and permitting the table to further descend to and remain in horizontal position. After the table is set for use the shade or flexible door 44 may be drawn down to the back board 20 or to the lower 95 shelf 36 to completely close the space above the shelves. After the flexible door 44 has been rolled up and the table swung up to vertical position, the flexible door may be drawn down to the top of the table or lower 100 door, as appearing in Fig. 1, and obviously the upper door or shade 44 may be drawn further downward for the purpose of covering the mirror 35, when it may be desired to 105 conceal the mirror or prevent reflections of objects or strong lights which might at times be objectionable. When the closet is closed, the curtains 46 and 47 obviously may be drawn more or less across the front of the 110 closet doors if so desired.

Having thus described the invention, what is claimed as new is—

1. A combination table and closet comprising a closet space, two studs fixed on two opposite sides respectively of the closet space at the front side thereof, two beams arranged at the inner side of the studs respectively and pivoted thereto for sole support of the beams, a table secured to the beams, two arms integral with the beams respectively and extending approximately to the opposite rear side of the closet space when the beams are horizontal, and a weight supported by said arms. 115

2. A combination table and closet comprising a closet space, two upright studs fixed on two opposite sides respectively of the closet space at the front side thereof, two beams arranged at the inner sides of the studs respectively, two pivot studs rig- 120 125 130

idly secured to the upright studs and extending loosely through the beams respectively, two arms fixed directly to the beams respectively and extending approximately 5 to the opposite rear side of the closet space when the beams are horizontal, a table secured to the beams, two links connected to said arms respectively, a hollow vessel supported by the links, granular weight substance arranged in said vessel, a frame connected to said beams and to said table between the beams, and a mirror secured in 10 said frame.

3. In a combination table and closet, a 15 table comprising two beams and a flat table member secured to one side of the beams, portions of the beams extending materially

beyond said member to constitute powerful counter-balance arms, a back-board secured to the table member and extending beyond 20 one side thereof, two pivot devices connected to the beams respectively, two upright studs supporting the pivot devices and thereby solely supporting the table, two pivot studs rigidly secured to said arms respectively, two link chains connected to said pivot studs, a hollow vessel supported by 25 said chains, and counter-balance weight substance loosely and removably arranged in said vessel.

In testimony whereof, I affix my signature on the 4th day of August, 1922.

CHARLES T. BOYER.
